UNITED STATES PATENT OFFICE.

JOHN HASKINS, OF BOSTON, MASSACHUSETTS.

FENDER FOR CARS.

SPECIFICATION forming part of Letters Patent No. 740,129, dated September 29, 1903.

Application filed February 21, 1903. Serial No. 144,428. (No model.)

To all whom it may concern:

Be it known that I, JOHN HASKINS, a citizen of the United States, residing at Boston, in the county of Suffolk and State of Massachusetts, have invented an Improvement in Fenders for Cars, of which the following description, in connection with the accompanying drawings, is a specification, like letters on the drawings representing like parts.

10 Cars used on tracks in the streets and run by electricity and automobile-cars in order to lessen their danger to pedestrians require a fender.

This invention has for its object the production of an automatic fender for use in connection with cars such as stated whereby a person coming in contact with the fender cannot be run over by the wheels of the car, but will be picked up and carried forward with

20 the car until the latter is stopped.

My improved fender comprises a frame and a plurality of platforms, each pivoted on or with relation to the frame and one platform pivoted to the other, and the innermost of the 25 two platforms has a hinged nose. The frame will preferably be so constructed and applied to the car-body, at either end thereof, that it may be shoved into or under the platform of the car when the car is going in one direction, the frame being pulled out to make the 30 fender operative when the car is moving in an opposite direction.

Figure 1 represents a sufficient portion of one end of a street-railway car with my fender in position to enable my invention to be understood, the full lines showing the fender in its inoperative position and the dotted lines showing it as operative to pick up a person that might be lying on the roadway. Fig. 2 35 is a perspective view enlarged.

The car A may be of any usual or suitable shape, and a portion of the body thereof may have a groove a , in which may be slid when desired the frame B. This frame at its outer 40 end sustains pivots b , on which are pivoted the legs c of the main platform C of the fender, said pivot being located between the ends of the legs c , the extremities of said legs having studs c' , that enter the side bars d of the main 45 part of the auxiliary platform D. The auxiliary platform has near its inner end at each side a stud c^2 , that enters a slot c^3 in each side

of the frame B. The front edge of the auxiliary platform D has connected to it by suitable hinges d' a nose D' . The device so far 55 described is capable of operating in two different ways.

Assuming that the main and auxiliary platforms are in the position represented by full lines, Fig. 1, should the front end of the main 60 platform strike a person and the person should fall over on the upper side of said platform he would also fall upon the nose D' of the auxiliary platform, and the latter, owing to the weight of the body of the person thereon, 65 would descend into dotted-line position, Fig. 1, and full-line position, Fig. 2, and the main platform would rise, so that the person would be held in a trough or basket made between the main and auxiliary platforms. Should, 70 however, a child or person fall on the track in front of the approaching car, the front end of the main platform would strike the person, and the main platform would be turned upwardly instantly into the dotted-line position, 75 causing the nose of the auxiliary platform to be dropped onto the roadway, as represented in Fig. 1, and the nose, properly shaped, would run under the body of the person and pick up said body and carry it with the car 80 until the car is stopped.

Having described my invention, what I claim as new, and desire to secure by Letters Patent, is—

1. A car-fender comprising a frame and a 85 main and auxiliary platform, the main platform being hinged to the frame and to the auxiliary platform, and the auxiliary platform being movable lengthwise of the frame.

2. A car-fender comprising a frame, a main 90 and auxiliary platform, the latter provided with a hinged nose, the main platform being pivoted with relation to the frame and jointed to the auxiliary platform, and the auxiliary platform being movable longitudinally of the 95 frame as and for the purpose set forth.

In testimony whereof I have signed my name to this specification in the presence of two subscribing witnesses.

JOHN HASKINS.
